UNITED STATES PATENT OFFICE.

FRANK J. REICHMANN, OF CHICAGO, ILLINOIS.

DESIGN FOR A CASING FOR INDUCTION COIL.

Application filed April 16, 1925. Serial No. 13,145. Term of patent 14 years.

To all whom it may concern:

Be it known that I, FRANK J. REICHMANN, a citizen of the United States, residing at 6830 Jeffery Avenue, Chicago, in the county of Cook and State of Illinois, have invented a new, original, and ornamental Design for Casing for Induction Coil, of which the following is a specification, reference being had to the accompanying drawing, forming part thereof.

Figure 1 is a front elevation of a casing for induction coil showing my new design; and

Figure 2 is a side elevation of said casing for induction coil.

I claim:—

The ornamental design for a casing for induction coil, as shown.

FRANK J. REICHMANN.
